[57] CLAIM

The ornamental design for a brush block and handle, as shown and described.

DESCRIPTION

FIG. 1 is a top plan view of a brush block and handle, showing my new design;

FIG. 2 is a right side elevational view, the left side elevational view being a mirror image thereof;

FIG. 3 is a front elevational view thereof;

FIG. 4 is a rear elevational view thereof;

FIG. 5 is a vertical sectional view thereof taken on line 5—5 of FIG. 1; and

FIG. 6 is a bottom plan view thereof.

FIG. 6
